UNITED STATES PATENT OFFICE.

MICHAEL WHALEN, OF NEW YORK, N. Y.

ATTACHMENT FOR NAILING MACHINES.

Application filed July 22, 1925. Serial No. 45,839.

This invention pertains to nailing machines, and has particular reference to an attachment for nailing machines employed in the manufacture of wooden boxes or shipping cases.

At the present time in nailing together the sides and ends of a box on a nailing machine, the operator must of necessity hold the ends of the box against the face of the machine and gage, and, at the same time, hold the side in juxtaposition to the end prior to and during the nailing operation of the machine. Usually the operator is furnished with a helper for holding the end in position while the operator applies and holds the side in juxtaposition to the end.

As an object, therefore, the invention comprehends a device consisting of an attachment for the nailing machine, which is operable by the initial movement of the actuating means for the nail-driving mechanism for engaging and holding the box end against the face of the machine and the gage while the operator manually positions and holds the side of the box in juxtaposition thereto prior to and during the nailing operation.

The invention particularly contemplates a device of this character which includes a swingable arm operable by the initial movement of the actuating means for the nail-driving mechanism in which the arm is provided with means to allow for a sufficient yieldability or give to prevent damage to the box end or to the operator of the machine should any part of his person be disposed in the path of movement of the arm during its movement to active position or its return movement.

The invention furthermore comprehends means for adjusting the throw of the arm to active position whereby to compensate for the variation in the thickness of the box ends.

As a further object the invention comprehends in a device of the character described, means carried by the free end of the arm for engagement with the box end which assumes a parallel position with respect to the box end and the face of the machine.

As a still further object the invention comprehends an attachment of the character set forth, which is comparatively simple in its construction and mode of operation, inexpensive to manufacture and install, and

which is thoroughly reliable and highly efficient in its purpose.

With the above recited and other objects in view, reference is had to the following specification and drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a fragmentary side view of a box-nailing machine equipped with an attachment constructed in accordance with the invention and illustrating the same in its active position;

Fig. 2 is a similar view on an enlarged scale, illustrating the position of the box and engaging arm prior to the swinging of the same to its active position;

Fig. 3 is a sectional plan view taken approximately on the line 3—3 of Fig. 2, illustrating, respectively, in full and dotted lines, the position of the arm in its active engaged position and its inactive disengaged position;

Fig. 4 is a fragmentary sectional plan view of the safety joint or connection between the arm and actuating means, to illustrate the manner in which the yieldability or give is accomplished;

Fig. 5 is a sectional plan view through the safety joint taken approximately on the line 5—5 of Fig. 3.

Referring to the drawings by characters of reference, A designates a portion of the frame of the machine having cross plates B against which the end members C and side members D of the box are adapted to be engaged. The nail plunger head E carrying the nail plungers F is mounted for vertical movement on the machine frame A in the usual manner for driving the nails fed through the nail feed chutes G, to the nail guide openings H.

The device constituting an attachment for the nail-driving machine, consists essentially of a forked or bifurcated bearing member 10, the vertically spaced furcations 11 and 12 of which are provided with aligned apertures to receive therethrough a pivot or fulcrum pin 13 upon which the inner end of the arm 110

14 is fulcrumed for horizontal swinging movement and upon which the superimposed bell cranks 15 and 16 are mounted also for swinging movement. The arm 14 is formed with a vertical beveled shoulder 17 on its upper face and the lower bell crank 15 is provided with a complementary vertical beveled shoulder 18 on the under face of its branch 19. The arm 14 is formed with an ear 20 and a coiled contractile spring 21 is connected respectively at its opposite ends with the ear 20 and with the free end of the branch 22 of the bell crank 15, whereby the said spring 21 normally exerts a tension to effect interengagement of the shoulders 17 and 18. The bell crank 15 is further provided on the upper face of its arm 19 with a vertical shoulder 23 and the bell crank 16 is formed on the under face of its branch 24 with a complementary vertical shoulder 25, which shoulders 23 and 25 are normally and yieldably maintained in engagement by means of a coiled contractile spring 26 connected respectively at its opposite ends to the free end of the branch 24 and to the ear 20. The opposite branch 27 of the bell crank 16 is pivotally connected at 28 with a connecting bar 29, which is in turn pivotally connected at its opposite end, as at 30, to a yoke 31 between the knuckles 32 thereof. The yoke 31 is formed with a series or plurality of transverse longitudinally spaced apertures 33 adapted to respectively align with the apertured bifurcated lower terminal 34 of the lower arm 35 of the bell crank 36, to receive through said aligned apertures a set screw 37, whereby the yoke may be adjustably associated with the bifurcated terminal of the lower bell crank arm 35. The remaining upper arm 38 of the bell crank has pivoted thereto, as at 39, a rock arm 40, which is connected by pin-and-slot connection 41 and 42 to the nail plunger head E for swinging the bell crank 36 on its fulcrum 43.

A coiled contractile spring 44 is connected at its opposite terminals, respectively, to the upper bell crank arm 38 and to a member 45 on a stationary part of the machine for normally effecting a return swinging movement of the bell crank arm to a normal position after each nailing operation of the machine. A shoe 46 is pivotally attached as at 47 to the free end of the arm 14, and said shoe is provided with a slotted extension 48, through the slot of which a stop rod 49 extends to limit the return outward swinging movement of the shoe under the influence of a coiled contractile spring 50, which is connected respectively to the lug 51 and to the arm 14. Under this arrangement it is obvious that the shoe will engage throughout its length the outer face of the box end irrespective of the angular disposition of the arm 14 with

respect thereto, so that when adjustment of the yoke is effected to compensate for variation in the thickness of the box ends, the shoe will insure a flat engagement with the box end to hold the same in position immediately prior to and during the nailing operation.

In use and operation, the initial downward movement of the nail plunger head E, when actuated by the operator, will effect a rearward swinging movement of the upper arm 38 of the bell crank lever 36, through the medium of the rock arm 40, which in turn will swing the lower arm 35 of the bell crank lever in a forward direction to cause the yoke 31 pivotally attached to the connecting bar 29, to swing the branch 27 of the upper bell crank 16 to which it is attached, in a left-hand direction. The branch 24 of the bell crank 16 connected by the coiled contractile spring 26 to the ear 20 of the arm 14, will swing said arm toward the left and rearwardly to cause the shoe to engage and hold the box end in flat contact with the face of the machine and in a rigid position while the operator holds the side D of the box in juxtaposition with the upper edge of the end immediately prior to and during the nailing operation of the machine. The spring 21 which connects the ear 20 of the arm 14, with the branch 22 of the bell crank 15, will cause the bell crank 15 to move in unison with the arm 14 and bell crank 16.

If the operator of the machine by any chance should dispose part of his person in the path of movement of the arm and shoe while the same is swinging to an active position, the tension of the springs 26 and 50 will be such as to prevent injury to the operator while the springs 50 and 26 also serve to cushion the shock incident to the swinging of the arm to engaging position with the box end C to prevent injury thereto.

After the nailing operation of the machine is completed and the nail plunger head E moves upwardly, the spring 44 will function to swing the upper arm 38 of the bell crank lever 36 forwardly, and the lower arm 35 thereof rearwardly to exert a pull on the connecting bar 29, which in turn will swing the branch 27 of the upper bell crank 16 toward the right, which by virtue of the interengagement of the shoulder 25 with the shoulder 23 of the lower bell crank 15, will cause such lower bell crank to be swung to the left in unison therewith. The spring 21 connected with the branch 22 in the bell crank 15 and with the ear 20 of the arm 14, will function to swing the arm forwardly and to the right to its normal inactive position. In event the operator disposes any part of his person in the path of movement of the arm when the same is swinging

to its normally inactive position, the spring 21 will cushion the shock and prevent serious injury.

From the foregoing it will thus be seen that the attachment devised enables a single operator for each machine, to accomplish practically the same amount of work as has heretofore been accomplished by an operator furnished with a helper; whereas, on the other hand, an operator and helper may accomplish considerably more work in a given length of time.

What is claimed is:

1. A device constituting an attachment for 15 nailing machines, comprising an element normally disposed in a position at one side and beyond the confines of the face of the machine and movable to an active position overlying said face for engaging and holding one of the members to be nailed against the said machine face in a proper relation to the nailing mechanism prior to and during the nailing operation, and an operative connection between the nailing-mechanism-actuating means and the element for moving the same to its active position.

2. A device constituting an attachment for nailing machines, comprising a swingable element normally disposed in a position at one side and beyond the confines of the face of the machine and movable to an active position overlying said face for engaging and holding one of the members to be nailed against the said machine face in a proper relation to the nailing mechanism prior to and during the nailing operation, and an operative connection between the nailing-mechanism-actuating means and the element for moving the same to its active position.

3. A device constituting an attachment for nailing machines, comprising a swingable arm normally disposed in an inactive position wholly disposed outside of the confines of the face of the machine and movable to an active position within the confines of said face and overlying the same for engaging and holding one of the members to be nailed against the said machine face in a proper relation to the nailing mechanism immediately prior to and during the nailing operation, and a connection between the actuating means for the nailing mechanism and said arm for moving the same from its inactive to its active position.

4. A device constituting an attachment for nailing machines, comprising a swingable arm normally disposed in an inactive position and movable to an active position for engaging and holding one of the members to be nailed in a proper relation to the nailing mechanism immediately prior to and during the nailing operation, and a connection between the actuating means for the nailing mechanism and said arm for moving the

same from its inactive to its active position, said means of connection including means for permitting yieldability of the arm during its swinging movements in opposite directions.

5. A device constituting an attachment for nailing machines, comprising a swingable arm normally disposed in an inactive position and movable to an active position for engaging and holding one of the members to be nailed in a proper relation to the nailing mechanism immediately prior to and during the nailing operation, a connection between the actuating means for the nailing mechanism and said arm for moving the same from its inactive to its active position, said means of connection including means for permitting yieldability of the arm during its swinging movements in opposite directions, and a foot element carried by the free extremity of the arm and connected thereto to permit of a flat engagement of the foot element irrespective of the angular disposition of the arm.

6. The combination with a box-nailing machine including a vertically movable nail plunger head, of a horizontally swingable arm mounted on the frame of the machine and normally disposed in an inactive position outside of the confines of the face of the machine, and mechanism connected with the arm and operable by the initial downward movement of the plunger head for swinging the arm to an active position within the confines and overlying the face of the machine to engage and hold the box end against said face of the machine in a proper position to receive the nails.

7. The combination with a box-nailing machine including a vertically movable nail plunger head, of a horizontally swingable arm mounted on the frame of the machine, and mechanism connected with the arm and operable by the initial downward movement of the plunger head for swinging the arm to a position to engage and hold the box end against the front of the machine in a proper position to receive the nails, said mechanism including a bell crank lever, a rock arm connecting one of the bell crank arms with the nail plunger head, a horizontal bell crank lever having one of its branches connected with the opposite arm of the bell crank lever and its opposite branch resiliently connected with the swingable arm, a subterposed bell crank lever having a shoulder on one of its branches, a complementary shoulder on the last-mentioned branch of the horizontal bell crank lever, and a spring connection between the remaining branch of the subterposed bell crank lever and the swingable arm.

8. The combination with a box-nailing machine including a vertically movable nail plunger head, of a horizontally swingable

arm mounted on the frame of the machine, and mechanism connected with the arm and operable by the initial downward movement of the plunger head for swinging the arm to a position to engage and hold the box end against the front of the machine in a proper position to receive the nails, said mechanism including a bell crank lever, a rock arm connecting one of the bell crank arms with the nail plunger head, a horizontal bell crank lever having one of its branches connected with the opposite arm of the bell crank lever and its opposite

branch resiliently connected with the swingable arm, a subterposed bell crank lever having a shoulder on one of its branches, a complementary shoulder on the last-mentioned branch of the horizontal bell crank lever, a spring connection between the remaining branch of the subterposed bell crank lever and the swingable arm, and a yieldable shoe carried by the swingable arm for flat contact with the box end irrespective of the angular disposition of the swingable arm with respect to the box end.

MICHAEL WHALEN.
